AUTOMOBILE SEAT COVER

Oliver F. Marston, Richmond, Va., assignor to
B. T. Crump Company, Inc., Richmond, Va., a
corporation of Virginia

Application February 29, 1952, Serial No. 18,723

Term of patent 14 years

(Cl. D14—6)

To all whom it may concern:

Be it known that I, Oliver F. Marston, a citizen of the United States and residing at Richmond, Virginia, have invented a new, original, and ornamental Design for an Automobile Seat Cover, reference being had to the accompanying drawing, forming part thereof.

In the drawing:

Fig. 1 is a front elevation of an automobile seat cover showing my new design;

Fig. 2 is a side elevation thereof; and

Fig. 3 is an enlarged partial side elevation thereof and a partial section taken along line 3—3 of Fig. 1.

The dominant features of my design reside in those portions shown by means of full lines.

I claim:

The ornamental design for an automobile seat cover, as shown and described.

OLIVER F. MARSTON.
